(57) **CLAIM**

The ornamental design for a sheet rack cart panel, as shown and described.

DESCRIPTION

FIG. 1 is a front perspective view of the sheet rack cart panel; FIG. 2 is a right side elevational view of the sheet rack cart panel of FIG. 1;

FIG. 3 is a left side elevational view of the sheet rack cart panel of FIG. 1;

FIG. 4 is a front elevational view of the sheet rack cart panel of FIG. 1;

FIG. 5 is a rear elevational view of the sheet rack cart panel of FIG. 1;

FIG. 6 is a top plan view of the sheet rack cart panel of FIG. 1;

FIG. 7 is a bottom plan view of the sheet rack cart panel of FIG. 1;

FIG. 8 is a front perspective view of a second embodiment of the sheet rack cart panel shown in FIG. 1, the only difference being the unclaimed features of the cart within which the sheet rack cart panel is mounted and the number and spacing of rows in the sheet rack cart panel, it being understood that all other surfaces are the same as those of the first embodiment shown in FIGS. 1-7; and,

FIG. 9 is a front perspective view of a third embodiment of the sheet rack cart panel shown in FIG. 1, the only difference being the unclaimed features of the cart within which the sheet rack cart panel is mounted, and the orientation and number and spacing of rows in the sheet rack cart panel, it being understood that all other surfaces are the same as those of the first embodiment shown in FIGS. 1-7.

The broken lines shown in the drawings are included for the purpose of illustrating environment and form no part of the claimed design.

1 Claim, 6 Drawing Sheets
